UNITED STATES PATENT OFFICE

PETER KARSTEN, OF DUSSELDORF, GERMANY, ASSIGNOR TO RHEINISCHE METALL-WAAREN- UND MASCHINENFABRIK SOMMERDA AKTIENGESELLSCHAFT, OF SOMMERDA, GERMANY, A CORPORATION OF GERMANY

WHEEL BRAKE

Application filed October 2, 1929, Serial No. 396,624, and in Germany November 12, 1928.

My invention relates to air-actuated wheel brakes of the type described in the specification of my co-pending patent application Serial Number 251,812. In this specification an air brake is described each of the brake jaws of which is actuated by a swing piston arranged in a casing, these pistons having between them an air-tight inflatable body. This hollow body is inflated by supplying air under pressure and by its expansion causes a swing motion of the pistons and of the brake jaws connected thereto. My invention has for its object to improve air brakes of this class as to the construction of the casing and arrangement of the swing pistons therein, whereby a uniform stress of the inflatable hollow body is obtained and both its durability and life is increased and a satisfying air-tight motion of the pistons in the casing is secured.

With these ends in view, my invention consists in the fact that each of the pistons is adapted to swing about a fulcrum which is arranged in the casing diametrically opposite to the fulcrum of the companion piston. This arrangement results in the fact of the pistons in swinging being always in a position parallel to one another.

In order that my invention can be more easily understood, a preferred embodiment of the same is illustrated by way of example in the drawing which shows a two-jaw brake intended for the wheels of an autocar. In this drawing

Figure 1 is a diametrical section through a wheel and the brake attached thereto,

Figure 2 is a sectional end view through the same parts with the brake in inoperative position, and

Figure 3 is a similar view with the brake applied.

Referring to these figures, a_1 and a_2 denote the two pistons that may swing about the pins b_1 and b_2 , respectively, the latter further connecting the outer parallel plates c_1 and c_2

of the casing to the jaw carrier which is fixedly mounted on the wheel axle. Normally to the plates c_1 and c_2 are arranged walls e and e_1 which are curved inside about the pins b_1 , b_2 . The plates c_1 , c_2 , walls e , e_1 , and the swing pistons a_1 , a_2 thus form a casing closed on all sides. In this casing is lodged the hollow rubber body f to which air for developing the braking action is conducted by means of a pipe or hose g which passes through the piston a_2 , and is connected with a suitable source of compressed air. The swinging motion of the pistons a_1 and a_2 is transmitted to the brake jaws i_1 and i_2 by rods h_1 and h_2 which are adjustable in length.

Upon the hollow rubber body f being inflated by air under pressure, the pistons a_1 , a_2 execute a swinging motion in parallel to one another, and at length assume the position shown in Figure 3, the shape of body f changing accordingly in such a manner that its rectangular cross section is maintained in the one (radial) direction while in the direction normal thereto the original approximately rectangular shape uniformly increases and the walls of body f expand uniformly.

What I claim and desire to secure by Letters Patent is:—

1. A fluid motor for compressed air brake systems, particularly for power driven vehicles, comprising two spaced parallel fixed plates, two curved wall sections extending between said plates in transverse perpendicular relation thereto, two swinging pistons pivoted at diagonally opposed points of said wall sections and having their free ends movable along the same, an inflatable elastic member enclosed between said pistons and wall sections, and a compressed air conduit passing through one of said pistons for conducting air under pressure to said inflatable member whereby said pistons are pivotally actuated in opposite directions to develop a braking action.

2. A fluid motor for compressed air brake

systems, particularly for power driven vehicles, comprising two spaced parallel fixed plates, two curved wall sections extending between said plates in transverse perpendicular relation thereto, two swinging pistons pivoted at diagonally opposed points of said wall sections and having their free ends movable along the same, an inflatable elastic member enclosed between said pistons and wall sections, and means for conducting air under pressure to said inflatable member whereby said pistons are pivotally actuated in opposite directions to develop a braking action.

15 In testimony whereof I have affixed my signature.

PETER KARSTEN.

systems, particularly for power driven vehicles, comprising two spaced parallel fixed plates, two curved wall sections extending between said plates in transverse perpendicular relation thereto, two swinging pistons pivoted at diagonally opposed points of said wall sections and having their free ends movable along the same, an inflatable elastic member enclosed between said pistons and wall sections, and means for conducting air under pressure to said inflatable member whereby said pistons are pivotally actuated in opposite directions to develop a braking action.

In testimony whereof I have affixed my
15 signature.

PETER KARSTEN.

CERTIFICATE OF CORRECTION.

Patent No. 1,810,354.

Granted June 16, 1931, to

PETER KARSTEN.

It is hereby certified that the above numbered patent was erroneously issued to "Rheinische Metallwaaren- und Maschinenfabrik Sommerda Aktiengesellschaft, of Sommerda, Germany, a Corporation of Germany", whereas said patent should have been issued to Rheinische Metallwaaren- und Maschinenfabrik Sommerda Aktiengesellschaft, of Sommerda, Germany, a Corporation of Germany, and Fritz Faudi, of Dusseldorf, Germany, as shown by the records of assignments in this office; and that the said Letters Patent should be read with this correction therein that the same may conform to the record of the case in the Patent Office.

Signed and sealed this 25th day of August, A. D. 1931.

(Seal)

**M. J. Moore,
Acting Commissioner of Patents.**
